(57) **CLAIM**

The ornamental design for a sharpened nose penetrator, as shown and described.

DESCRIPTION

FIG. 1 is a perspective view showing my new design;

FIG. 2 is a side view thereof;

FIG. 3 is a front end view thereof;

FIG. 4 is a rear end view thereof;

FIG. 5 is a side view of an alterative embodiment of my new design; and,

FIG. 6 is a front end view thereof.

The broken line showing of external hardware in FIGS. 1–6 is for illustrative purposes only and forms no part of the claimed design.
